UNITED STATES PATENT OFFICE

168,901

PORTABLE GRINDER

William R. Maclay, Endicott, N. Y., assignor to
Ingersoll-Rand Company, New York, N. Y., a
corporation of New Jersey

Application March 26, 1952, Serial No. 19,055

Term of patent 14 years

(Cl. D37—1)

To all whom it may concern:

Be it known that I, William R. Maclay, a citizen of the United States, residing at Endicott, in the county of Broome, State of New York, have invented a new, original, and ornamental Design for a Portable Grinder, of which the following is a specification, reference being had to the accompanying drawing, forming part thereof, and in which

Figure 1 is a top plan view of a portable grinder embodying my new design;

Figure 2 is a side elevational view thereof, and

Figure 3 is an elevational view taken from the right of Figure 2.

I claim:

The ornamental design for a portable grinder, substantially as shown.

WILLIAM R. MACLAY.
